LESTER H. LOEFFEL, OF NEW HAVEN, CONNECTICUT, ASSIGNOR TO THE BERGER BROTHERS COMPANY, OF NEW HAVEN, CONNECTICUT

CORSET CONSTRUCTION

Application filed December 17, 1927. Serial No. 240,892.

This invention relates to a concealed opening construction where it is desired to provide a concealed slot or other opening through the body of a fabric without a seam. It is applicable to various articles, including garments such as corsets. I shall describe the invention in connection with a corset provided with a concealed slot of my improved construction adapted for the passage of an abdominal 5 porter strap, but it is to be clearly understood that the invention is not limited to this particular application, but is applicable to various other uses in connection with fabric articles where a concealed and well reenforced 10 slotlike opening is desired.

It is customary in the prior art where it is desired to pass a strap freely through the body of the corset or the like to provide open or unstitched portions in appropriate seams, 15 or if there happens to be no seam at the point where the strap must pass through the corset, to slit the body of the corset to provide an opening, the fabric of the corset body being strengthened in various ways around the slit. 20 The present invention is directed in a specific aspect to an opening of the latter type.

According to the prior art, in making openings of this sort the material of the body of the corset around the slit is hemmed, leaving 25 a rather unsightly opening through which the straps pass. It is an object of the invention to provide an improved form of opening which is relatively simple, and in which the opening itself is effectively concealed.

Another object of the invention is to provide an opening in the corset or other fabric body in which means is provided for strengthening the body around the opening more effectively than the corresponding means here- 30 fore known.

An additional object of the invention is to provide an opening in a corset or other fabric body and strengthening means for the body around the opening, which is less bulky than 35 those previously known.

To these and other ends the invention consists in the novel features and combination of parts to be hereinafter described and claimed.

In the drawings:

Fig. 1 is a fragmentary view of a corset, showing an opening therein, according to my invention;

Fig. 1A is a sectional view along line 1A—1A of Fig. 1;

Figs. 2-5 are views showing intermediate steps in the formation of the opening;

Fig. 6 shows the opening in a finished state; and

Figs. 7-11, inclusive, are sectional views along lines 7—7, 8—8, 9—9, 10—10, 11—11 of Figs. 2, 3, 4, 5 and 6, respectively.

I have shown in Fig. 1 as an illustration of a preferred embodiment of my invention a corset generally designated by the reference numeral 12 and made up, generally speaking, of a number of gores or sections 13, 14, 15 and 16, connected together by means of seams 17, 18, 19 and 20, and provided with suitable means for connecting the ends thereof together, such as eyelets 21.

Under the front of the corset 12 is an abdominal supporter 22, having secured thereon a plurality of straps 23, 24, and 25, passing freely through one of the seams 18 to the exterior of the corset, the seam 18 being provided with an open or unstitched portion 26 for this purpose. Attached to the corset body adjacent to and in the seam 19 is a strap 27 having thereon a buckle 28 engaging strap 23, while the gore 15 is provided with an opening 29, to be hereinafter described in detail, through which pass straps 30 and 31 of sacro-iliac pad 32, having thereon buckles 33 and 34 engaging straps 24 and 25, respectively.

From the above description it will be readily understood that the straps 24, 25, 30 and 31, pass freely through the corset body to transmit pressure on the abdominal pad 22 to sacro-iliac pad 32, the buckles 33 and 34 providing a ready means for adjusting these straps.

The present invention is directed in particular to the form of opening generally designated by the reference numeral 29, and in which the invention is carried out by slitting the gore 15 longitudinally, as at 35, and transversely as at 36 and 37, to form two relatively long narrow tabs 38 and 39 joining the corset body along lines 38^a and 39^a, respec-

tively, which are displaced in any desired manner into the position shown in Fig. 7, where they are on the same side, and preferably the inside of the corset body. Tape 40, or other suitable binding means, is folded along a central longitudinal line to provide two-plies 41 and 42, between which the tab 38 is received, as shown particularly in Figs. 3 and 8. The tape 40 is then stitched to the 10 corset body along the line 38^a where the tab 38 joins the body, the tape 40, or other binding means, being preferably of such a width that when so stitched to the corset the edge 43 of the tab 38 is half way between the fold 15 of the tape and the line 38^a where the tab 38 joins the corset body. A tape 44 may be applied to the tab 39 in the preceding manner to provide two-plies 45 and 46, between which the tab 39 is received, the edge 47 of the tab 20 39 being half way between the fold in the tape and the line 39^a where the tab joins the corset body. The distance the tab extends into the tape may be varied to a considerable extent by using various widths of tape, but 25 in the preferred form is proportioned as above, for a purpose to be hereinafter pointed out.

After the tapes 40 and 44 have been applied to their respective tabs, one of the tabs, in 30 the present instance, the tab 38, is folded under the tab 39. The ends of the tapes 48, 49, 50 and 51 are then locked to the fabric body by suitable means such as rows of stitching 52 and 53, and if desired, the tapes are locked 35 to the fabric at any intermediate point or points, as shown for example at 54. The ends 48, 49, 50 and 51 beyond the stitching may then be cut off, as shown in Fig. 6. The overlapping tapes 40 and 44 provide an opening 55 therebetween which is effectively concealed from view by the fact that each tape, or other binding material, when folded presents a width substantially twice the width of 40 the tab to which it is attached, whereupon 45 each tape extends substantially from the point where its associated tab joins the body of the corset to the point where the other tab joins the body of the corset.

From the above description of my invention 50 it will be seen that I have provided a relatively simple form of opening in a corset or other body through which a strap, or other means, may be readily passed, and in which there is no unsightly opening or bulky construction. All of the raw edges of the tabs 55 38 and 39 are carried within the tapes 40 and 44, so that there is no danger of these portions of the corset unraveling.

While I have shown a preferred embodiment 60 of my invention, it is to be understood that the same is not to be limited to all the details shown but is capable of modification and variation within the spirit of the invention and the scope of the appended claims.

65 What I claim is:—

1. In a corset or the like, a one piece body portion, said body portion having a slit within its margins, said slit being intersected at each of the ends thereof by transverse slits forming two adjacent tabs, strips of binding material secured one to each of said tabs, said strips projecting beyond the tabs so as to lie in overlapping relation and providing an opening through the corset body therebetween. 70

2. In a corset or the like, a one piece body portion, said body portion having a slit within its margins, said slit being intersected at each of the ends thereof by transverse slits forming two adjacent tabs, strips of binding material secured one to each of said tabs, said strips projecting beyond the tabs so as to lie in overlapping relation and providing an opening through the corset body therebetween, said strips of binding material being secured to said body adjacent the ends of said opening. 75

In witness whereof, I have hereunto set my hand this 15th day of December, 1927.

LESTER H. LOEFFEL. 80
